 graphie m. b. H., Berlin, Germany, a corpora-
 tion of Germany

Application October 24, 1934, Serial No. 749,727
 In Germany October 25, 1933

5 Claims. (Cl. 179—171)

This application relates to a circuit for and method of modulating oscillations comprising the use of multi-grid tubes, especially screen grid tubes.

- 5 5 Plate potential modulation which has proved successful in triode tubes, is attended with difficulties whenever tubes comprising a plurality of grids are used, say, screen-grid tubes. There is a demand in practice for such use on the ground 10 10 that the screen-grid tube offers advantages over the triode. For instance, the plate-to-grid capacitance in a screen grid tube is lower. One chief disadvantage residing in plate potential modulation with a screen-grid tube consists in 15 15 the risk of over-loading the screen-grid whenever the plate potential is low. The screen grid may be protected by making the biasing voltage of the control grid from the outset strongly negative. When this is done the power delivery of the 20 20 tube decreases considerably even when the plate voltage is high.

Now, according to this invention overloading of the screen grid electrode is avoided without sacrifice of the power output by insuring that the 25 25 screen-grid voltage, upon diminution of the plate voltage, is likewise reduced. In other words, screen grid potential and plate potential are modulated under co-phasal conditions. This method offers the further merit that a modulation 30 30 characteristic that is straight inside wide limits is obtainable, thereby insuring linear modulation over a large potential range.

This fact will become clearer by reference to Figs. 1-8 of the drawings, of which Figs. 1, 3, 5, 7, 35 35 represent the relation between the plate potential E_a and the screen-grid potential E_s , while Figs. 2, 4, 6, 8 illustrate the modulation characteristics, i. e., the relation between the plate alternating voltage e_a and the plate direct current voltage 40 40 E_a , in the presence of constant radio frequency control grid alternating voltage, which are insured in the presence of conditions shown in Figs. 1, 3, 5, 7, between the potentials E_a arising at the plate and E_s at the screen grid.

45 45 Figures 9 to 13 inclusive illustrate various circuit arrangements each including means for applying modulation potentials simultaneously to the anode and another electrode in a thermionic tube.

50 50 In the case of Fig. 1, conditions are so arranged that there prevails a linear relationship between applied plate voltage E_a and applied screen-grid voltage E_s . In the example here chosen, the ratio between the two is 25%, in other words, the 55 55 screen-grid voltage amounts to only one-fourth of the plate voltage. The assumption is moreover made that both the modulation of the plate voltage as well as that of the screen-grid voltage is 100% e. g. 0 to 400 volts and 0 to 100 volts, respectively. The modulation characteristic ob-

tained from the tube under these circumstances is shown in Fig. 2. In this graph, e_a is radio frequency anode voltage plotted as ordinates against anode voltage plotted as abscissa, it being understood that the relation between anode voltage E_a and screen grid voltage E_s is maintained as shown by the graph in Fig. 1 while plotting the graph of Fig. 2. The characteristic is straight only within the median ranges.

5 10 In Fig. 3 linear relations are shown between the plate potential E_a and the screen-grid potential E_s , but in this instance the plate potential is modulated 100% and the screen-grid voltage only 50%. But the relationship between the two voltages is not constant here. The modulation curve obtained under these conditions has a shape as shown in Fig. 4. Note that modulating the screen grid between 50 and 100 volts while the anode is modulated between 0 and 400 volts has resulted in the lower end of the graph of Fig. 2 15 20 being straightened as shown in the graph of Fig. 4. Thus, we are attaining a more desirable modulation characteristic.

15 25 In Fig. 5 the relations between plate voltage E_a and screen-grid voltage E_s are again linear. While here the plate voltage is modulated 100% the screen-grid voltage is modulated 150%. Here, by modulating the screen grid between -50 and 100 volts while the anode is modulated between 0 and 400 volts, I have straightened the upper end 30 30 of the modulation characteristic graph, as shown in Fig. 6, but in doing so have made the lower end of the graph less linear than in the prior cases.

35 35 In the case of Fig. 7 the relations between plate voltage E_a and screen-grid voltage E_s are not linear. The modulation voltage is impressed upon the screen grid by way of means possessing non-linear action, the said means in the case of Fig. 9 40 40 consisting of a triode tube. By producing a bilinear relation between the anode voltage and screening voltage, as shown in Fig. 7, the ideal relation between the anode radio frequency voltage and the anode direct current voltage is obtained, as shown in Fig. 8. The lower part of the graph of Fig. 7 is linear and rises steeply and then rises less steeply, but is still linear. This relation between the applied anode voltages and screen grid direct current voltages is accomplished 45 45 by producing a suitable distortion of the screen grid controlling voltage as it is applied.

50 50 To illustrate circuit schemes wherein modulation characteristics of the kind shown above may be obtained, a number of exemplified embodiments are shown in Figs. 9-13. Referring to the same, R is the tube to be modulated, K is the direct current blocking condenser, D a radio frequency choke-coil, S the oscillation circuit, and M the modulation transformer.

55 55 The circuit organization of Fig. 9 serves for 60 60

realizing the characteristics shown, in Figs. 1 and 2. The tube R has its control grid and cathode connected to a carrier wave source not shown. The anode of R is coupled to the cathode 5 of R by a blocking condenser K and a tuned circuit S. The latter is coupled to a load circuit which, for purposes of illustration is shown as an aerial system. Modulating potentials are applied from a source not shown to the primary 10 winding of transformer M, the secondary winding of which is connected to a potentiometer P. One terminal of P is connected to the anode of R by way of a radio frequency choke D. A point on P is connected to the screen electrode 15 of R. The other end of P is connected by the source of direct current potential to the cathode of R. The relation of four to one may be maintained between the anode voltage and screen grid voltage, as shown in Fig. 1, by adjusting the 20 point on P, to get the modulation characteristic as shown in Fig. 2. Operating states as shown in Figs. 3 and 5, and Figs. 4 and 6, respectively, are obtainable by circuit arrangements of the kind illustrated in Figs. 10-12. In 25 Fig. 10 a special counterdirect current voltage source G is provided which serves the purpose of preventing the screen grid from obtaining a voltage equal to the plate voltage. In the case of Fig. 11 the alternating voltages to be fed to 30 the screen grid are obtained by tapping the modulation transformer M. In both circuits the relation between the anode voltage E_a and screen voltage E_s shown in Figs. 3 and 5 may be obtained by the source G and movable points on P 35 and the secondary of M, respectively, to obtain the modulation characteristic as shown in Figs. 4 and 6, respectively. In Fig. 12 an exemplified embodiment for a modulation transformer is shown in which the plate and the screen grid 40 alternating potentials are generated in distinct secondary windings. By selecting the proper relation between the secondary windings of M and the primary winding and by moving the tap connected at the lower end of the secondary 45 winding connected with the screen grid electrode along the anode source, the desired relation between the anode potential and screen grid potential may be obtained. Circuits 10, 11, and 50 12 are in other respects quite similar to the circuit of Fig. 9.

In a circuit scheme as shown in Fig. 13 it is feasible to insure working conditions of the kind depicted in Figs. 7 and 8. In the screen-grid lead is included a non-linear device N which here, for instance, consists of a supplementary 55 electron tube. To distort the screen-grid voltage, however, recourse may be had to any other known arrangement. The device N comprises a thermionic tube having its control grid connected to a point on the secondary winding of M and its anode connected to the screen grid of R. The cathode of the tube in N is connected to a point on a source of potential in series with a resistance connected between the 60 screen grid of R and the lower end of the secondary winding of M. By properly biasing the control grid of the tube in N, the bi-linear relation between the anode voltage E_a and the screen grid voltage E_s shown in Fig. 7 may be 65 obtained. Note here that the first part of the graph is linear and rises steeply, as shown in

Fig. 3, while the upper end of the graph is linear but rises less steeply, as shown in Fig. 4. The bilateral relation between the screen grid voltage and anode voltage combine to give a modulation characteristic linear throughout its length, as 5 shown in Fig. 8.

I claim:—

1. A device for modulating carrier wave oscillations at signal frequency comprising, a thermionic tube having an anode, a cathode, and a control grid electrode, and a screen grid electrode, a carrier wave energizing circuit connected to the control grid and cathode of said tube, a source of modulating potentials, a resistance connected between a point on said source 10 of modulating potentials and the anode of said tube, a connection between said source of modulating potentials and the cathode of said tube, and an impedance of non-linear character connected between the screen grid of said tube and 15 said source of modulating potentials.

2. In a device for modulating carrier wave oscillations at signal frequency, a thermionic tube having an anode, a cathode and a control grid and a screen grid electrode, a carrier wave 20 energizing circuit connected to the control grid and cathode of said tube, an impedance on which signaling potentials may be impressed, a circuit connecting said impedance between the anode and cathode of said tube, and a circuit including an impedance of non-linear character 25 connecting a point on said first named impedance to the screen grid of said tube.

3. In a modulation system, a thermionic tube having an anode, a cathode, a control grid, and 30 a screen grid, a circuit connected with the control grid and cathode of said tube for applying carrier wave oscillations to be modulated to the control grid and cathode of said tube, an impedance connected with a source of modulating 35 potentials, a source of direct current potential connecting one terminal of said impedance to the cathode of said tube, a circuit connecting the other terminal of said impedance to the anode of said tube, and a circuit including a non-linear 40 impedance connecting the screen grid of said tube to a point on said first impedance.

4. A system as recited in claim 3 in which a source of potential is interposed in said circuit connecting said screen grid to said point on said 50 first impedance.

5. In a modulation system, a thermionic tube having an anode, a cathode and a control grid and a screen grid, a circuit for applying carrier wave oscillations to be modulated to the control 55 grid of said tube, a modulation frequency transformer having a primary winding which may be connected to a source of modulating potentials, said transformer having a secondary winding, a source of direct current potentials connecting 60 the secondary winding of said transformer between the anode and cathode of said tube, an additional thermionic tube having an anode, a cathode and a control grid, a circuit connecting the anode-to-cathode impedance of said additional 65 tube between the screen grid of said first named tube and a point on said secondary winding, and a connection between the control grid of said additional tube and a point on said secondary winding.

JOHANNES ROHNFELD.
